UNITED STATES PATENT OFFICE.

THERON L. HILES, OF NILES, MICHIGAN.

APPARATUS FOR MIXING AIR AND GAS.

Application filed May 31, 1919, Serial No. 301,112. Renewed May 31, 1923.

To all whom it may concern:

Be it known that I, THERON L. HILES, a citizen of the United States, residing at Niles, in the county of Berrien and State 5 of Michigan, have invented certain new and useful Improvements in Apparatus for Mixing Air and Gas, of which the following is a specification.

The invention pertains generally to gas 10 heating and lighting systems and more particularly to means for supplying under pressure variable quantities of air and gas mixed in a predetermined proportion, the quantity of the mixture supplied being controlled by 15 the amount consumed.

The general object of the invention is to produce a gas and air mixing apparatus of a practical character which is economical in operation and otherwise of high efficiency.

20 More specifically, one object of the invention is to provide improved means for varying the quantity of the mixture produced at any time exactly in accordance with the quantity required for consumption. In prior

25 devices of this general character the mixture produced by the apparatus over and above the demand therefor, is conducted back into the apparatus where it is again compressed. This obviously results in a

30 waste of energy. Moreover, the recompression of the mixture results in the generation of heat which necessitates the provision of means such as a water jacket through which cooling water is circulated to prevent

35 the apparatus from becoming heated to such an extent as to be incapable of functioning properly. To avoid these difficulties, I provide a variable capacity compressor which is adapted to supply to the service main at 40 any time a quantity of mixed air and gas sufficient to supply the demand only.

A further object of the invention is to provide means of improved construction and arrangement for maintaining substantially 45 constant the proportion of air and gas constituting the mixture produced, it being a well known fact that the resistance of air and gas vary disproportionately with the enlargement or restriction of the inlet ports therefor, thus necessitating in the mixture of varying quantities of air and gas a disproportionate varying of the sizes of their respective inlet ports.

When the gas to be mixed with air in the 50 apparatus is supplied from a community station, the pressure thereof in the main, as

will be readily apparent, fluctuates with the variation in the quantity of gas consumed. Another object of my invention is to provide improved means for stabilizing 60 the flow of gas through the inlet port of the apparatus.

A further important object of the invention is to provide means for regulating the quality or richness of the mixture, by supplying at will a greater or less amount of the fuel gas to compensate for the variations in the B. t. u. value thereof.

Still another object of the invention is to provide means operative when the apparatus is idle to prevent leakage of gas through the supply ports.

The objects of the invention thus generally stated, together with other and ancillary advantages, are attained by the construction and arrangement illustrated in the accompanying drawings forming part hereof, in which Figure 1 is a vertical section taken on line 1—1 of Fig. 3, of an apparatus embodying the features of my invention. 60

Fig. 1^a is a diagrammatic view showing a slightly modified arrangement. Fig. 2 is a fragmentary central vertical sectional view through the apparatus. Fig. 3 is a vertical section taken on line 3—3 of Fig. 1. Fig. 65

4 is a transverse section taken on line 4—4 of Fig. 1. Fig. 5 is a similar view taken on line 5—5 of Fig. 2. Fig. 5^a is a horizontal section taken in the plane of line 5^a—5^a of Fig. 1. Fig. 6 is a fragmentary section 70

taken on line 6—6 of Fig. 2 and showing details of construction. Fig. 7 is a fragmentary enlarged sectional view taken on line 7—7 of Fig. 1. Fig. 8 is a similar view taken on line 8—8 of Fig. 7. Fig. 9 is a 75

fragmentary perspective view showing a detail of construction. Fig. 10 is a fragmentary sectional view taken on line 10 of Fig. 2. Fig. 11 is a front side elevation of a slightly different form of apparatus. Fig. 100

12 is a transverse enlarged sectional view taken on line 12—12 of Fig. 11. Fig. 13 is a fragmental vertical section on an enlarged

scale taken on line 13—13 of Fig. 11.

The apparatus comprises generally a main 105 casing 14 providing in its upper portion a cylindrical casing 15 within which is rotatably mounted a rotor 16. Said casing and rotor form a compressor to which a mixture of air and gas is supplied by way of an 110 elongated chamber 17 opening into one side of the casing 15. In the construction shown

in Figs. 1 to 4, this chamber 17 extends downwardly from the compressor and opens into a mixing chamber 18 of a casing 19 on the forward side of the casing 14 and forming a part thereof. Air and gas are supplied to this mixing chamber by means to be hereinafter described, embodying the means for varying the relative sizes of the gas and inlet apertures and the means for controlling the admission of gas at different pressures. 20 indicates a duct opening from the casing 15 at the side opposite the chamber 17 and forming an outlet for the mixture after having been compressed, and 21 is a pipe connecting said outlet with a chamber formed in the lower portion of the casing 14 by means of a diaphragm 22 which is operatively associated with the compressor to vary the capacity thereof as more fully hereinafter set forth.

The casing 14 comprises a lower or base portion 14^a rectangular in form, the upper portion 14^b of which is somewhat reduced in size to form a vertical guideway 23 in which is mounted a plunger support 24 for a flexible member 25. The plunger support 24, which is arranged to be supported by the diaphragm 22 in a manner to be later set forth, is also rectangular in form, having a sliding but snug fit in said guideway 23, and the upper wall 26 of said support is curved to conform to the curvature of the adjacent stationary wall of the compressor casing. The flexible member 25 is secured to said wall 26 of the plunger support, as by means of rivets 27, and its opposite ends are curved upwardly so as to slidably engage the peripheral wall of the casing 15 on opposite sides thereof. In width said member 25 is equal to that of the casing 15 and thus constitutes a movable wall or raceway for the rotor 16. The raceway is completed by the exposed portion 28 of the cylindrical wall of the casing 15. In order to accommodate the added thickness of the member 25, the portion 28^a of the peripheral wall, which underlies the member 25, is offset outwardly.

The rotor 16, which may be of any suitable or preferred construction, is keyed onto a shaft 29 mounted eccentrically of the casing 15, and carries a plurality of radially movable blades 30 held by centrifugal force, in the operation of the apparatus, in sliding engagement with the raceway of the compressor. Herein the rotor is mounted in the uppermost portion of the casing, and it will be readily apparent, by reference to Fig. 2, that by moving the plunger support 24 and with it the flexible member 25 toward and from the axis of the rotor, the effective eccentricity of the latter is decreased or increased and the capacity of the compressor thereby varied accordingly. In such movement of the plunger support 24 the opposite

ends thereof slidably engage with the peripheral wall portion 28^a at opposite sides of the compressor casing. It will be understood that any suitable means may be provided to rotate the shaft 29 to drive the compressor.

For the purpose of enabling the mixture of air and gas to enter the compressor from the chamber 17, the latter is made of greater width than the raceway (Fig. 4); and to permit the discharge of the compressed mixture from the compressor the outlet duct 20 opening from the compressor casing is also made of greater width than the raceway (Fig. 6). Herein the chamber 17 and the duct 20 are shown as forming part of the casing 14, the upper portion of which may consist of a portion 14^c (Fig. 2) formed integrally with the portion 14^b, and separate sections 14^d and 14^e suitably secured together and to the portion 14^c are respectively formed integral with the chamber 17 and duct 20.

In order that the blades 30 of the rotor may slide freely from the portion of their raceway formed by the cylindrical wall 28 of the casing onto the flexible member 25, fingers 31 (Figs. 2, 9 and 10) are provided on the opposite upper ends of said member and have inturned ends 32 adapted to operate in narrow grooves 33 formed in the peripheral wall portion 28 of the casing. These fingers are made of a length slightly greater than the extent of vertical movement of the member 25 so that when said member is in its lowermost position (see Fig. 10) or higher, the blades 30 of the rotor while traveling between the portion 28 of the peripheral wall of the casing and the flexible member 25, and vice versa will be supported by the fingers against outward movement into the offset portion 28^a of the cylindrical wall of the casing. In Fig. 10 the upper limit of the offset or enlarged portion 28^a of the peripheral wall of the casing is shown at 34. In order that the air and gas which may find its way beneath the flexible member 25 may freely escape when the member moves toward its seat upon the peripheral wall of the casing, the grooves 33 for the fingers 31 may be continued downwardly substantially to the top of the plunger support, as shown at 33^a (Figs. 2 and 4).

The means for controlling the position of the plunger support 24 and thereby of the flexible member or raceway 25, will now be described: Referring to Figs. 1, 2, 3 and 5 the plunger support 24 is mounted on the upper end of a rod 35, the lower end of which is fixed centrally of the diaphragm 22. The edges of said diaphragm are herein shown as clamped between two sections of the base portion 14^a of the casing 14 and the diaphragm thus forms a chamber in the lower portion of the casing which is at all

times in communication with the outlet duct 20 of the compressor through the pipe 21. Said duct constitutes the service main of the apparatus. It will be seen that as the pressure in the service main rises and falls in accordance with the consumption of the mixture, the diaphragm 22 and thereby the rod 35 and flexible raceway 25 are caused to rise and fall.

10 To facilitate the diaphragm in thus imparting vertical movement to the flexible member 25, means are preferably provided for partially counterbalancing the vertically movable parts. Any suitable means may be employed for this purpose. Herein I have shown a counterweight 36 slidably mounted on the rod 35 so as to be guided thereby and having laterally extending arms 37. At the free ends of these arms are mounted a pair 20 of levers 38 and 39 pivotally mounted on brackets 40 and 41 which are fixed on opposite sides of the casing; and said levers each have a slotted pivotal connection with a collar 42 fixed on the rod 35. The proportion 23 and arrangement of the parts is such as to resist an upward movement of the diaphragm, except when the pressure on its under side exceeds a predetermined amount. This ensures the maintenance of the required pressure in the service main. In order that the effect of the counterweight may be varied at will, the pivot of one of said levers is in the form of a rock-shaft which carries an arm 43 having in turn a weight 44 adjustable 30 thereon. It will be seen that by adjusting the position of the weight 44 the counteracting effect of the counterweight 36 may be readily varied. To permit of such adjustment the casing is provided with an opening 45 (Fig. 3) which may have a suitable closure 46.

Referring now to the means for regulating the admission of air and gas to the apparatus: The casing 19 in which is provided the mixing chamber 18 (Fig. 3) is also provided with an air inlet chamber 47 and a gas inlet chamber 48 (Figs. 3 and 5^a). These chambers are formed by dividing the portion of the casing 19 below the chamber 50 18 centrally thereof by means of a partition 19^a, (Fig. 5^a). To permit the passage of air and gas from these chambers 47 and 48 to the mixing chamber 18, ports 49 and 50, 49^a and 50^a (Figs. 1 and 3) are provided in the inner wall of said casing 19. Said ports 55 49 and 50 open respectively into by-passes 51 and 51^a formed in a pendent portion 52 (Figs. 3 and 5^a) of the plunger support 24. The ports are herein made rectangular in form, and the ports 49 and 50 open respectively from the air and gas chambers 47 and 48 into said by-passes 51 and 51^a, and the ports 49^a and 50^a open from their respective by-passes into the mixing chamber 18. In the outer wall of the casing 19 apertures 53 and 54 are provided opening respectively into the chambers 47 and 48. It will be seen that gas supplied to the chamber 48 through the opening 54 will, if the port 50 is open, pass into the by-pass 51^a and thence through the port 50^a into the mixing chamber 18. Similarly air admitted into the chamber 47 through the port 53 will pass through the port 49 into the by-pass 51 and thence through the port 49^a into the mixing 75 chamber. From the mixing chamber the combined gases are conducted to the compressor by means of the elongated chamber 17.

If desired, the pendent portion 52 of the plunger support 24 may be so constructed 80 that as the plunger rises with the decrease in the consumption of the mixture, the admission of air and gas is restricted. To this end said portion 52 has a dependent plate 55 adapted to decrease the size of the apertures formed by the ports 49 and 50 as the rate of consumption decreases and the plunger support 24 rises.

It will be seen that with a decrease in the consumption of the mixture, not only is the 90 capacity of the compressor decreased, but the volume of the mixture admitted thereto is also diminished. Owing, however, to the fact that the resistances of air and gas do not vary in the same proportion as the sizes 95 of their respective inlets are varied by the plate 55 in the movement of the plunger support 24, I preferably provide means for disproportionately varying the sizes of said inlets. This means comprises a plate or 100 slide 56 (Figs. 1 and 3) mounted within the casing 19 and slidably through the partition 19^a therein. A portion of the slide extends into each of the chambers 47 and 48 and slidably engages the inner wall of the casing 105 in which are located the ports 49 and 50, the slide being of sufficient length to partially cover both of these ports as shown in Fig. 1 (dotted lines). It will be seen that when the slide is moved in either direction it will 110 serve to increase the size of the aperture of one of said ports and correspondingly decrease the size of the aperture of the other one of said ports, and in order that this may be accomplished as the rate of consumption 115 varies, I have provided means by which the up and down movements of the plunger support and its depending portion impart a lateral movement to the slide. To this end the lower edge of the slide is provided with 120 rack teeth 57 (Fig. 1) adapted to mesh with a pinion 58 which is fixed against rotation but slidable on a shaft 59. This shaft 59 extends through a depending ear 60 of the casing 19 and is operatively connected to the 125 pendent portion 52 of the plunger support so as to be rotated thereby as the support rises and falls.

Preferably, the means for accomplishing this result is so arranged that the slide may 130

be moved manually for the purpose of adjustment. Thus, referring to Figs. 7 and 8, the shaft 59 has mounted on its inner end a loose clutch member 61 and also has a fixed clutch member 62. A spring 63 on the shaft bearing between the portion 60 of the casing and a collar 64 fixed on the shaft, serves to normally hold the clutch members in holding engagement. Said clutch members are mounted within an aperture 65 (Figs. 7 and 8) formed in the lower portion 14^a of the casing, and the loose clutch member 61 carries an arm 66 passing through a staple 67 in the plate 55. It will be seen that in the normal position of the parts the movement imparted to the plunger support 24 by the pressure in the diaphragm chamber will also be imparted to the slide 56, and the parts are so arranged that as the plunger support rises with the decrease in consumption of the mixture, the air inlet is increased and the gas inlet restricted; and when the consumption increases the reverse action takes place. The extent of such movement to be imparted to the slide may of course be readily controlled as desired by properly proportioning the connection between it and the vertically movable plate 55.

In order to facilitate the adjustment of the slide the rod or shaft 59 is provided on its free end with a hand wheel 68, and the rod may be provided with a pointer 69 movable relative to a dial 70 on the casing 19. When it is desired to adjust the slide relative to the arm 66 and plate 55, it is only necessary to pull the rod outwardly until the clutch member 62 is disengaged from the clutch member 61, the latter being held against outward movement by the arm 66 which is held to the plate 55 by the staple 67. In this movement of the rod the pinion 58 thereon remains in mesh with the rack teeth 57 on the slide so that by rotating the rod the slide can be moved as desired independently of the plunger support 24.

When the gas to be supplied to the apparatus is taken from a city or other community supply main, where the pressure varies almost continually, it becomes necessary to provide means for preventing such variation in pressure in the supply main from affecting the volume of gas admitted to the apparatus. Herein, to accomplish this result, I provide a gas inlet port, the area of which is adapted to be varied with the rise and fall of the pressure in the supply main. Said port is formed by the inner end of a pipe line 71 leading to the opening 54 of the chamber 18. To control said port I provide a valve plate or member 72 slidable in a casing 73 (Fig. 4) which may be formed integral with an annular ring 74 (Fig. 4) forming part of the pipe line 71. A bellows diaphragm 75, is adapted to receive pressure from the supply main to operate said valve

plate 72, and to this end a pipe 76 leading from the pipe line 71 opens into one end of the bellows diaphragm, and the other end of the latter has a sliding connection through the medium of a link 77 with a lever 78. Said lever is pivoted to a bracket 78^a at its upper end, and at its lower end slidably engages the free end of a rod 79 carried by the valve member 72 and extending through one end of the casing 73. It will be seen that as the pressure in the supply main varies the pressure upon the bellows diaphragm 75 also varies, an increase of pressure in the main serving to effect a closing movement of the valve member and a decrease of pressure serving to effect an opening movement of said member. By thus varying the size of the inlet port controlled by the valve member 72 in proportion to the pressure in the supply main, the volume of gas admitted through the inlet port is effectively controlled so that the fluctuating pressure in the gas main is prevented from affecting the supply of gas to the apparatus. In order that the position of the valve member 72 may be adjusted to permit the passage of the required volume of gas at different pressures in the main, the effective length of the lever 78 may be made variable. Herein the supporting bracket 78^a to which the lever is pivoted, is provided with a slot 80 (Fig. 1) to enable the pivotal point of the lever to be varied relative to the point of its connection with the link 77. By this means the parts may be readily adjusted as desired, such for example, that when the pressure in the main falls to one inch, water column, the passage-way through the pipe line is wholly unrestricted by the valve member, and as the pressure in the gas supply main increases, the valve member gradually closes said passage-way.

Summarizing the operation of the apparatus as above set forth: The shaft 29 of the compressor being driven from a suitable source of power (not shown) to operate the compressor, suction in the elongated chamber 17 is created. Thereupon, air entering the inlet chamber 47 through the opening 53, at atmospheric pressure, and gas entering the inlet chamber 48 through its inlet port, are drawn through the by-passes 51 and 51^a into the mixing chamber 18. From said chamber the mixture passes into the chamber 17. The admission of gas through the inlet port is controlled by the operation of the bellows diaphragm 75 actuated by the pressure of the gas in said supply main to move the valve member 72, which is interposed in the gas supply port or passage-way. From the compressor the air and gas, thoroughly mixed and compressed, pass into the outlet duct 20 or service main. As the amount of mixture supplied to the service main exceeds the demand therefor,

the increasing pressure in the service main is transmitted to the diaphragm 22 through the pipe 21, and the diaphragm acting through the rod 35 and the plunger support 24 moves the flexible raceway 25 upwardly toward the axis of the compressor rotor, thereby decreasing the capacity of the compressor and hence the amount of mixture supplied to the service main. Such upward movement of the plunger support 24 also causes the pendent portion 52 and valve plate 55 to rise to gradually close the inlet ports 49 and 50, thus decreasing the volume of air and gas supplied to the mixing chamber. At the same time the upward movement of the plate 55 acting through the arm 66, shaft 59 and pinion 58, causes the slide 56 to increase the aperture through the port 50 and to restrict the aperture through the port 49. Such disproportionate variation in the sizes of the air and gas ports is effected in order to compensate for the disproportionate variation in resistance of air and gas as the sizes of their respective inlet apertures vary. When the surplus mixture has been consumed so that the pressure in the service main varies, the valve plate 55, slide 56 and movable raceway 25 operate reversely to produce an increased supply of mixture.

If desired, the control of the admission of air and gas into the apparatus by means such as the slide valve 56 (Fig. 1) which is directly associated with the plunger support 24 may be omitted. Thus in the form of apparatus shown in Figs. 11 to 13, a chamber 17^a terminating below the compressor casing constitutes the mixing chamber for the air and gas communicating with the pressure inlet. To this end it is provided with a central partition 81 in its lower end (Fig. 13) forming an air inlet chamber 82 and a gas inlet chamber 83. The former chamber is open at its lower end to permit the entrance of air, while the latter chamber is closed at its lower end and in one side has an opening 84 into which a gas inlet pipe 84^a enters. Suitable means may be provided for controlling the area of the gas inlet port formed by the pipe 85, in accordance with the variation in pressure in the supply main, as, for example, that shown in Figs. 1, 3 and 4. It will be understood that in this construction the variable capacity of the compressor is depended upon entirely to vary the quantity of mixture produced by the apparatus, this being accomplished in the manner above set forth in connection with the first form of the apparatus described.

In order to prevent leakage of gas from the apparatus when it is idle, either by way of the gas inlet or from the compressor, I preferably provide means for automatically closing both the air and gas inlet cham-

bers when the compressor is idle, whereby to cut off communication between said chambers and the mixing chamber which in this instance is formed by the chamber 17^a as above set forth. Thus referring to Figs. 11 and 13, I provide butterfly valves 85 and 85^a in the chambers 82 and 83, both fixed upon a rod 86 passing through both chambers as well as the partition 81. On the free end of said rod is a crank arm 87 which is connected by a link 88 to a crank arm 89 carried by the lower end of a rock shaft 89^a (Fig. 11). The latter is pivotally mounted in brackets 89^b carried by the compressor casing adjacent the shaft thereof and on its upper end carries an arm 89^c arranged to be swung by a suitable governor mounted on an extended end 29^a of said shaft. Herein, said governor comprises a fixed collar 90 on the shaft and a sliding collar 91 connected by a pair of jointed links 92 carrying weights 93 at their joints and connected by a spring 94. The sliding collar 91 has an annular groove 95 therein for engaging a yoke 96 on the crank arm 89. It will be seen that when the compressor shaft 29 is rotated in the operation of the apparatus, the governor will rock the shaft 89^a and through the crank arm 89, link 88 and crank arm 87 rotate the rod 86 carrying the valves 85 and 85^a. The parts are so proportioned and arranged that as soon as the apparatus is set in operation both of said valves will be swung into open position, the restriction of both inlets being removed simultaneously so as to permit of the admission of the air and gas in the proper proportion while the valves are being opened.

It will be seen that I have produced an air and gas mixing apparatus of an advantageous and efficient character. Various means of practical construction are provided to meet the peculiar conditions naturally arising in actual practice. The means for disproportionately varying the sizes of the air and gas ports is very simple in construction and arrangement, embodying a single positively operated valve member imparting the attribute of certainty to the operation. Moreover, the difficulty arising from the fluctuation in pressure of the gas in the service main is effectively overcome. At the same time the volume of mixture supplied to the service main is quickly and accurately regulated in accordance with the demand without necessarily burdening the compressor, effecting a saving in motive power and also eliminating useless wear and tear upon the parts.

It will also be observed that by varying the capacity of the compressor the volume of air and gas supplied to the service main is limited to that actually required for consumption at any given time. If the demand increases, producing a fall in pres-

sure in the service main below that determined by the weights, the compressor promptly responds to increase the supply; and if the demand decreases, the rise in pressure in the service main causes a corresponding decrease in the volume supplied. None of the mixture therefore is returned by a by-pass to the compressor inlet, as in prior apparatus, and the result is that 10 the proportion of air and gas constituting the mixture is maintained substantially constant notwithstanding the rise and fall of the pressure in the service main. This follows from the fact that the return of a 15 variable quantity of the mixture from the compressor outlet to the inlet is a disturbing factor in the system in that it produces at the compressor inlet a suction of varying intensity depending upon the quantity 20 of the mixture returned. The result is that the proportion of air to gas entering the compressor, as predetermined by the relative sizes of the inlet openings, is destroyed since the air and gas, being of 25 different specific gravities, respond differently to a suction of varying intensity. In the present instance, the intensity of the suction at the compressor inlet is maintained substantially constant. Hence the 30 proper proportion of air and gas in the mixture, for combustion purposes, with a resulting high efficiency of the system is assured.

The variable capacity compressor is of 35 very simple construction and operation, and it will be seen that its use is not limited to air and gas mixing apparatus, but may be employed in other connections which will readily suggest themselves to 40 those skilled in the arts. I also desire to have it understood that while the invention is herein illustrated and described with considerable particularity, it is not to be limited, in the interpretation of the appended claims, except as may be necessitated by the prior state of the art.

I desire particularly to point out that the apparatus is not one limited to the mixing of air with a single kind of gas or to the 50 mixing of air with gas from a single source, for obviously the construction may be readily varied without departing from the spirit and scope of my invention to enable the mixing of several gases, it being only necessary to provide additional inlet ports and 55 controlling means therefor of the character set forth. Thus, in Fig. 1^a I have shown diagrammatically an arrangement in which a gas inlet port 97 is provided in addition to air and gas inlet ports 98 and 99. This port 97 may be controlled by a slide 100 which may be operated in any suitable manner but independently of the slide 56^a which controls the ports 98 and 99. It will be 60 apparent that by means of such additional 65

inlet port, an enriching gas may be introduced into the apparatus for the purpose of increasing the heating or B. t. u. value of the mixture.

I claim as my invention:—

1. An apparatus of the character described comprising, in combination, a compressor of the positive blower type having an inlet and an outlet, a mixing chamber communicating with said inlet, air and gas inlet chambers communicating with said mixing chamber, a closed chamber having a diaphragm, means establishing communication between said compressor outlet and said diaphragm chamber, and means actuated in the movement of said diaphragm to vary the capacity of said compressor whereby to limit the volume of mixture passing therethrough to that required for consumption at any given time. 70

2. An apparatus of the character described comprising, in combination, a compressor having an inlet and an outlet, a mixing chamber communicating with said compressor, air and gas inlet chambers communicating with said mixing chamber, a closed chamber having a diaphragm, said compressor embodying a casing having a rotor mounted eccentrically thereof and a movable peripheral wall, and means actuated in the movement of said diaphragm to move said wall toward and from the axis of the rotor to vary the capacity of the compressor so as to limit the volume of mixture discharged to that actually required for 90 consumption. 95

3. An apparatus of the character described comprising, in combination, a main casing providing a compressor in its upper portion provided with a movable wall, an auxiliary casing at one side of the main casing and provided with an air inlet chamber and a gas inlet chamber each having an inlet and an outlet, and a mixing chamber having an inlet, an outlet communicating with the compressor inlet, a closed chamber having a diaphragm, means establishing communication between said closed chamber and said compressor outlet, and means operable in the movements of said diaphragm 105 to actuate said movable wall to vary the volume of the mixture produced and including means providing valved communication between said inlet chambers and said mixing chamber. 110

4. An apparatus of the character described, comprising, in combination, a main casing providing a compressor in its upper portion having an inlet and an outlet, an auxiliary casing at one side of the main casing and providing air and gas inlet chambers each having an outlet port, and a mixing chamber communicating with the compressor inlet and having an inlet, a closed chamber having a diaphragm, means estab- 125 130

lishing communication between said closed chamber and said compressor outlet, and means actuated in the movement of said diaphragm to vary the capacity of said compressor and including means establishing communication between the outlet ports of said inlet chambers and the inlet of said mixing chamber.

5. An apparatus of the character described, having, in combination, a casing having a compressor therein provided with an inlet and an outlet, a mixing chamber communicating with said compressor inlet, said casing having an air inlet port and a gas inlet port, means establishing communication between said inlet ports and said mixing chamber, a closed chamber having a diaphragm and communicating with the compressor outlet and means comprising a single valve member and a part actuated in the movement of said diaphragm and having a gearing connection with said valve member whereby to disproportionately vary the relative sizes of said ports as the pressure in the compressor outlet rises and falls.

6. An apparatus of the character described comprising, in combination, a casing having a compressor therein provided with an inlet and an outlet, a mixing chamber communicating with said compressor inlet, said casing having an air inlet port and a gas inlet port, a closed chamber having a diaphragm and communicating with the compressor outlet, means actuated in the movement of said diaphragm to establish valve-controlled communication between said ports and said mixing chamber, and separate valve means also actuated in the movement of said diaphragm to vary disproportionately the relative sizes of said ports.

7. An apparatus of the character described comprising, in combination, a casing having an outlet duct, a compressor adapted to discharge into said outlet duct, a mixing chamber communicating with said compressor, said casing having an air inlet port and a gas inlet port, a slide valve adapted to be actuated by the pressure of the gas at the source of supply for varying the area of the gas inlet port as the pressure in the supply main fluctuates, and means establishing communication between said inlet ports and said mixing chamber operable directly by the pressure of the mixture at the compressor outlet to vary the volumes of air and gas passing therethrough.

8. An apparatus of the character described having, in combination, a casing having an outlet duct, a compressor in the casing communicating with said duct, a mixing chamber communicating with said compressor, an air inlet chamber and a gas inlet chamber normally communicating with said mixing chamber when the apparatus is in

operation, and means operatively associated with the compressor whereby to cut off communication between the inlet chamber and the mixing chamber when the apparatus is idle.

9. An apparatus of the character described having, in combination, a casing having an outlet duct, a compressor in the casing discharging into said duct, a mixing chamber communicating with said compressor, an air inlet chamber and a gas inlet chamber arranged to communicate with said mixing chamber, a valve for each of said chambers, and a governor operatively associated with the compressor and said valves whereby when the compressor is in operation communication between the inlet chambers and said mixing chamber is open, and when the compressor is idle such communication is closed.

10. An apparatus of the character described comprising, in combination, a casing having a mixing chamber, a gas inlet port and an air inlet port each communicating with said mixing chamber, said casing having a cylindrical portion communicating with said mixing chamber and having an outlet duct, a rotor mounted eccentrically within said cylindrical portion of the casing and having radially movable blades, a member constituting a movable peripheral wall providing a raceway for the blades of the rotor, and means operable with the rise and fall of pressure in said outlet duct to vary the position of said member relative to said rotor whereby to limit the volume of the mixture passing through the compressor to that actually required for consumption.

11. An apparatus of the character described comprising, in combination, a casing having a mixing chamber, a gas inlet port and an air inlet port each communicating with said mixing chamber, said casing having a cylindrical portion communicating with said mixing chamber and having an outlet duct, a rotor mounted eccentrically within said cylindrical portion of the casing having radially movable blades, a member constituting a movable wall for the compressor thus formed adapted to be slidably engaged by said rotor blades, a closed chamber within said casing communicating with said duct and having a diaphragm, and means actuated in the movement of said diaphragm to vary the position of said member relative to said rotor whereby to equalize the volume of air and gas drawn from the inlet ports into the compressor and the volume of the mixture discharged by the compressor.

12. An apparatus of the character described comprising, in combination, a casing having a mixing chamber, a gas inlet port and an air inlet port each communicating

with said mixing chamber, said casing having a cylindrical portion communicating with said mixing chamber and having an outlet duct, a rotor mounted eccentrically 5 within said cylindrical portion of the casing, a member constituting a movable wall for the compressor thus formed, a closed chamber within said casing communicating with said duct and having a diaphragm, and 10 means actuated in the movement of said diaphragm to limit the volume of air and gas passing through the compressor to that required for consumption by varying the position of said member relative to said 15 rotor, said means comprising a supporting member for said member slideable vertically in the casing, a counterweight operatively connected with said supporting member, and adjustable means for varying the counter- 20 balancing effect of said counterweight.

13. In an apparatus for mixing air and gas, a compressor having an inlet and an outlet, a mixing chamber, means for admitting quantities of air and gas in a predetermined proportion to said chamber, and 25 means operable by the pressure at the compressor outlet to equalize at all times the volume of the mixture entering, passing through and leaving the compressor.

14. An apparatus of the character described comprising, in combination, a compressor provided with an inlet and an outlet, means for conducting quantities of air and gas to the compressor inlet, a closed 35 chamber having a diaphragm, means establishing communication between said closed chamber and said compressor outlet, and means actuated in the movement of said diaphragm to vary the capacity of the compressor in accordance with the volume of the mixture consumed at any given time.

15. An apparatus of the character described comprising, in combination, a casing having an air inlet port and a gas inlet port, 45 a mixing chamber, means establishing communication between said ports and said mixing chamber, a compressor having an inlet and an outlet, means establishing communication between said mixing chamber and the inlet of the compressor, a closed chamber having a diaphragm, a pipe connecting said compressor outlet with said closed chamber, a member guided for vertical movement in said casing and operatively associated with 55 said diaphragm to be moved up and down in the movements of the diaphragm, and a slide for governing said inlet ports operatively associated with said vertically movable member so that in the movements of the latter the slide restricts one of said inlet ports and enlarges the aperture of the other inlet port.

16. In an apparatus of the character described comprising a casing having a compressor therein and having a gas inlet port

and an air inlet port, and means for disproportionately varying the sizes of the apertures through said ports as the quantity of air and gas drawn through said ports varies, said means comprising a vertically movable 70 member in said casing, a slide for governing said inlet ports, a rock shaft having a gearing connection with said slide, and an arm operatively associated with said vertically movable member so that in vertical 75 movements of the latter a lateral movement is imparted to the slide.

17. In an apparatus of the character described comprising a casing having a compressor therein and having a gas inlet port 80 and an air inlet port, and means for disproportionately varying the sizes of the apertures through said ports as the quantity of air and gas drawn through said ports varies, said means comprising a vertically movable 85 member in said casing, a slide for governing said inlet ports, a rock shaft having a gearing connection with said slide, and an arm operatively associated with said vertically movable member so that in vertical movements of the latter a lateral movement is imparted to the slide, said rock shaft having a disengageable connection with said member to permit of the adjustment of the slide independently of the member.

18. An apparatus of the character described, comprising, in combination, a casing having an air inlet port and a gas inlet port, 90 a mixing chamber, means establishing communication between said ports and said mixing chamber, a compressor communicating with said mixing chamber, and including a member movable to vary the capacity thereof, and means operatively associated with said member for disproportionately 100 varying the relative sizes of said inlet ports as the volumes of air and gas drawn into said mixing chamber by said compressor vary.

19. An apparatus for mixing air and gas comprising, in combination, a compressor having an inlet and an outlet, a mixing chamber communicating with the compressor inlet and also with an air inlet port and two gas inlet ports, valve means operable by the pressure of the mixture at the compressor outlet to control the air inlet port and one of said gas inlet ports, and means independent of the last mentioned means for controlling the other one of said gas inlet ports. 110

20. An apparatus for producing a combustible gaseous mixture comprising, in combination, a compressor having an inlet and an outlet, a mixing chamber communicating with the compressor inlet and also with an air inlet port and two gas inlet ports, means controlled directly by alterations in the pressure of said mixture to control one of said gas inlet ports, and means independent of the last mentioned 125 130

controlling means for controlling the other inlet port.

21. The method of producing a combustible mixture of gas and air which consists in supplying to a compressor quantities of gas and air through a pair of inlet ports in predetermined proportions, controlling such supply automatically in accordance with the pressure of the mixture at the compressor outlet, and supplying to the compressor at will a variable quantity of gas to compensate for any variation in the B. t. u. value of the gas forming part of the mixture.

15 22. The method of producing a gaseous mixture for combustion which consists in supplying to a compressor in the desired proportions the gases which constitute the mixture, and limiting the volume of the mixture passing through the compressor at any time to that actually required for consumption.

25 23. The method of producing a combustible gaseous mixture which consists in supplying to a compressor in the desired proportions the gases constituting the mixture, and controlling the volume of the mixture discharged by the compressor into the service main by varying the volumetric capacity of the compressor to limit the volume passing through the compressor at any given time to that actually required for consumption at that time.

35 24. In a system for supplying a variable quantity of air and gas for combustion, the combination of a compressor having an inlet for air and gas, means for admitting air and gas to said inlet in a predetermined proportion, a service main into which the compressor is adapted to discharge the mixture of air and gas, and means controlled by the pressure in the service main for limiting the volume of air and gas discharged by the compressor into the service main in accordance with the volume of the mixture actually required for consumption.

40 25. In an apparatus for supplying a variable quantity of air and gas for combustion, a compressor having an inlet and an outlet, means for admitting to the inlet a supply of air and gas in a predetermined proportion, and means controlled by the pressure at the compressor outlet for varying the volumetric capacity of the compressor whereby to limit the volume of mixture discharged from the compressor to that required for consumption.

45 26. In a gaseous fuel supply system, the combination of a compressor having an inlet and an outlet, a service main communicating with the outlet, means for supplying air and gas to the compressor inlet, means for controlling the flow of air and gas to said inlet in a predetermined proportion, and means controlled by the pressure in the

service main for limiting the volume of air and gas discharged by the compressor substantially to the volume required for consumption at any given time, the means for controlling the volume of air and gas flowing to the compressor being also controlled by the varying pressure in the service main.

70 27. In a gaseous fuel supply system, the combination of a compressor having an inlet and an outlet and comprising an annular casing having a peripheral wall, a rotor mounted in said casing and having a plurality of radially movable blades for slidably engaging said wall, means for admitting air and gas to the compressor inlet in a predetermined proportion, and means controlled by the compressor at the compressor outlet for effecting relative movement between said peripheral wall and said rotor whereby to limit the volume of the mixture entering the compressor to that required for consumption at any given time.

80 28. In a gaseous fuel supply system, the combination of a positive type blower or compressor comprising an annular casing having a movable peripheral wall portion and a rotor mounted in said casing and having a plurality of radially movable blades, means controlled by the compressor at the compressor outlet for admitting a plurality of gases to the compressor in a predetermined proportion to constitute the gaseous mixture, and means also controlled by the pressure at the compressor outlet for moving said wall portion to vary the volumetric capacity of the compressor whereby to limit the volume of mixture discharged from the compressor at any given time to that actually required for consumption at that time.

90 29. In a gaseous fuel supply system, the combination with a service line, of a compressor comprising an annular casing having an inlet and an outlet, said outlet communicating with the service line, means for admitting quantities of air and gas in a predetermined proportion to said inlet, a rotor mounted in said casing so as to operatively engage therewith to effect the positive movement of the gaseous fluid therethrough, and means controlled by the pressure at the outlet of the compressor operable to equalize at all times the volume entering, passing through and discharged into the service line.

105 30. In a gaseous fuel supply system, the combination with a service line, of a compressor for delivering a variable volume to said service line as determined by the demand, said compressor comprising an annular casing, a movable inner peripheral wall, and a rotor adapted to effect the positive movement of fluid through the casing; means for admitting the gases to constitute the mixture in a predetermined proportion to the compressor inlet, and means operable automatically to move said wall with re-

spect to the casing whereby to equalize at all times the volume entering and passing through the compressor with that discharged into the service line.

- 5 31. The combination with a service line, of a compressor comprising an annular casing, a rotor mounted in said casing and having a plurality of radially movable blades, and means controlled by the pressure in the

10 service line whereby to limit the volume of

fluid passing through the compressor to that required for consumption at any given time, said means including a peripheral wall movable toward and away from the rotor to vary the capacity of the compressor and capable of bending or flexing in such movement as its radius decreases or increases. 15

In testimony whereof, I have hereunto set my hand.

THERON L. HILES.
